UNITED STATES PATENT OFFICE.

EPPA H. RYON, OF PASADENA, CALIFORNIA. ASSIGNOR TO CROMPTON & KNOWLES LOOM WORKS, OF WORCESTER, MASSACHUSETTS, A CORPORATION OF MASSACHUSETTS.

THREAD-CUTTING MECHANISM FOR LOOMS.

Original application filed August 29, 1921, Serial No. 496,351. Divided and this application filed January 24, 1925. Serial No. 4,548.

This application is a division of Serial No. 496,351, filed by me August 29, 1921, and relates particularly to the thread cutting mechanism shown but not claimed in said

5 prior application.

It is one important object of my invention to provide a thread cutter and actuating connections therefor so constructed that the cutter may be removed from operative position 10 and returned thereto without disengagement of the actuating connections, while at the same time the cutter is rendered inoperative so long as it is out of cutting position.

Further features of my invention relate to 15 the provision of an improved ratchet device for actuating certain moving parts of the mechanism to an improved thread cutter, and to other arrangements and combinations of parts which will be hereinafter described 20 and more specifically pointed out in the appended claims.

A preferred form of the invention is shown in the drawings in which

25 Fig. 1 is a plan view of a thread cutter embodying my invention; and

Fig. 2 is a side elevation thereof.

Referring to the drawings, I have shown portions of a loom frame 10, a lay 11, a rear shuttle box plate 12, and a weft carrier 30 transferrer 14, mounted upon a fixed pivot 15. A stand 20^a is secured to the loom frame 10 and is provided with guides 21—22 for a slide 23, which is yieldingly held in rearward position by a spring 24 mounted within 35 the slide.

One end of the spring 24 engages a shoulder at the rear of the slide 23 and the other end engages a projection 26 on the stand 20^a. This projection 26 acts as a stop to limit 40 rearward movement of the slide and also provides a bearing for a sliding rod 25, fixed in the slide 23 and acting to center the spring 24.

The front end of the slide 23 or of the 45 rod 25 engages suitable connections (not shown) through which the loom will be stopped if the slide 23 is moved forward by engagement with a widely misplaced shuttle.

An arm 27 is secured to the rear end of 50 the slide 23 and pivotally supports a roll 28 adapted to engage a slightly misplaced shuttle and force it into the shuttle box. If

the shuttle is too widely misplaced, the shuttle directly engages the roll 28 and moves the slide 23 forward against the pressure of the 55 spring 24, thus stopping the loom.

A friction belt 31 is supported by a roll 32 adjustably secured to the rear end of the slide 23 by a stud 33. A belt 31 also passes around a feed roll 34 mounted on the stud 35 at the front of the slide 23. An idle or guide roll 36 is mounted on a stud 37, vertically adjustable in a flange 38 of the slide 23, and engages the belt 31 to guide and tension the same.

60 A friction plate 40 is pivoted at 41 on a depending projection of the slide 23 and is yieldingly pressed against the under side of the belt 31 by a light coil spring 42.

The feed roll 34 has internal ratchet teeth 43 engaged by a feed pawl 44 mounted on a bell crank 45 also pivoted on the stud 35. A spring 46 is connected to one end of the feed pawl 44 and to a lug or projection on the bell crank and holds the pawl in engagement 70 with the ratchet teeth. An arm 47 is secured to the bell crank 45 and is connected by a telescoping link 48 to an arm 49 depending from the transferrer 14. Each downward movement of the transferrer thus provides 75 an operating or feed stroke of the pawl 44.

80 A thread cutter is mounted on the slide 23 and is positioned between the shuttle placer and the friction belt. The cutter comprises a jaw 50 secured to the slide 23 by screws 51 and a movable jaw 52 pivoted to the slide at 53 and having a depending arm 54 connected by a link 55 to one arm of the bell crank 45. Downward movement of the transferrer thus also operates through 85 the link 55 to close the thread cutting jaws 50 and 52 and sever the thread at the time of transfer.

90 Reference to Fig. 2 will show, however, that the closing of the cutting jaws is delayed until the pivotal connection of the link 55 and bell crank 45 has moved downward to and past the dead center. The operation of the transferrer being substantially at front center for the lay, the action 95 of the thread cutter is substantially later than the effective operation of the shuttle placer. This allows the friction belt to secure a firm hold on the thread before the

knives act. The severed end is then held by the friction belt until the temple cutter cuts the thread at the selvage.

When the shuttle is too widely misplaced, 5 no weft carrier transfer can occur, and it is desirable that the operation of the thread cutter be prevented. This result is attained by the provision of the roll 28, which engages a widely misplaced shuttle and moves 10 the thread cutter and slide forward, while at the same time the two portions of the telescoping link 48 are partially separated so that downward movement of the transerrer will not cause any corresponding operation 15 of the bell crank 45 and of the parts associated therewith. Upon the return of the slide 23 to rearward position, the telescoping parts of the link 48 immediately resume operative relation.

20 My improved thread cutter and the actuating mechanism therefor are peculiarly adapted for use in a loom in which a fresh weft carrier is transferred on the same beat of the lay on which weft exhaustion is indicated, as the cutter operates after front center. The friction belt 31 co-operating 25 with the friction plate 40 provides a reliable and effective device for grasping the weft during the operation of the thread cutter and 30 for thereafter holding the severed weft end which projects from the selvage until the regular temple cutter operates to sever the weft close to the edge of the cloth.

Particular attention is called to the fact 35 that the ratchet mechanism by which the belt 31 is advanced intermittently is positioned within the ratchet wheel or pulley 45, so that it is protected from injury and so that the pawl 44 is always in position to engage the ratchet teeth 43. All parts which 40 support the belt 31 are mounted on and movable with the slide 23, a marked improvement over the construction shown in my prior Patent No. 1,009,997, issued November 28, 1911.

Having thus described my invention and the advantages thereof it will be seen that I have provided a very simple and efficient thread cutting mechanism which is well 50 adapted for the purposes indicated, and which is not liable to displacement or failure when in use.

In consequence, I do not wish to be limited to the details herein disclosed otherwise than 55 as set forth in the claims, but what I claim is:—

1. In a loom having weft replenishing mechanism, a slide mounted for movement relative to the replenishing mechanism, a 60 thread cutter mounted on said slide, thread holding means including a continuous fric-

tion surface mounted entirely on said slide to engage and move the weft thread into cutting position and under continuous uniform tension in every position of said slide, and operating connections between said replenishing mechanism, said cutter and said holding means. 65

2. In a loom having weft replenishing mechanism, a thread cutter, a slidably mounted support for said cutter, a friction belt carried entirely on and movable with said support to present the weft thread to the cutter, said belt being under continuous uniform tension in every position of said slide, and a separable connection between the replenishing mechanism and said cutter and weft-presenting means, said connection operating said cutter and said presenting means at transfer but permitting said cutter 75 and said presenting means to remain inoperative when the support is moved forward from normal position by a widely misplaced shuttle. 80

3. In a loom having a lay and weft replenishing mechanism, in combination, a thread cutter, means to present a weft thread to said cutter, operating mechanism for said presenting means and cutter, a support in which said parts including said operating 90 mechanism are mounted for movement as a unit toward and from the lay in continuous operative relation, and a connection between the replenishing mechanism and said operating mechanism effective to give the latter 95 operative movements when the replenishing mechanism operates, but permitting said cutter, said presenting mechanism and said operating mechanism to move bodily and as a unit with the lay to an abnormal forward 100 position independently of the weft replenishing mechanism and thereby disabling the operating connection and preventing thread cutting action. 105

4. In a loom having weft replenishing mechanism, a thread cutter, a slidably mounted support for said cutter, means carried entirely on and movable with said support to present the weft thread to the cutter, and a link between said replenishing mechanism and said cutter, said link having telescoping and freely separable members. 110

5. In a loom, in combination, a slide, a thread cutter thereon, a feed pulley and a guide pulley on said slide, a friction belt on said pulleys, said feed pulley having internal ratchet teeth, a feed pawl mounted within said feed pulley and engaging said teeth, and actuating means for said pawl. 115

In testimony whereof I have hereunto affixed my signature. 120

EPPA H. RYON.
